UNITED STATES PATENT OFFICE.

JOHN I. NASMITH, OF ELTHAM, LONDON, ENGLAND.

BOX, PACKING CASE, AND THE LIKE.

Application filed July 18, 1922. Serial No. 575,914.

To all whom it may concern:

Be it known that I, JOHN IRVING NASMITH, of 12 Glenshiel Road, Eltham, London, S. E. 9, England, have invented new and useful Improvements in Boxes, Packing Cases, and the like, of which the following is a specification.

The invention relates to packing cases and the like constructed of cardboard or wood or both combined. Such cases as usually made leave much to be desired; they do not well resist the forces from outside to protect the contents, nor do they well resist the static forces and still less the dynamic forces exerted by the contents in handling and transit. Also such cases have to be fastened up in such a manner that they must be partly destroyed to open them and are easily pilferable without showing any external traces of interference, if merely nailed and cannot be used again or returned in usable condition.

The object of the present invention is to construct a case which, when packed, can be closed by simple means and the operation of closing puts one part of the case in tension and the other in compression, thus forming a very rigid box or case apart from the contents, and at the same time to so arrange it that the closing device is the only part that has to be destroyed or damaged to open the case and dismember it into its several parts and which is unpilferable without destroying or visibly damaging such device and finally to provide that the dismembered case is collapsible, easily stored in quantities in small compass, undamaged in opening and consequently reusable or returnable in little space to the factory for reuse.

In order that the invention may be easily understood I append a sheet of drawings showing the various parts of the box or case, together with means of closing it and holding it together during transit.

Figure 1 is a perspective view, showing the body frame hereinafter described, made in one piece.

Figure 2 is an edge view, showing the body frame collapsed.

Figure 3 is a perspective view, showing the body frame made in a plurality of pieces.

Figures 4 and 5 are fragmentary sectional views, showing end portions of the body, provided with end frames constituting abutments.

Figure 6 is a perspective view, showing separately an abutment-forming end frame

differing in construction from those shown by Figures 4 and 5.

Figure 7 is a fragmentary perspective view, showing a portion of the body frame provided with abutments, and differing in construction from the body frame shown by the preceding figures.

Figure 8 is a section on line 8—8 of Figure 7.

Figure 9 is a perspective view of one of the two members hereinafter called the top and bottom members, said member being straightened.

Figure 10 is a view similar to Figure 9, showing the member flexed.

Figure 11 is a perspective view of a complete box or case, including the parts shown by Figures 1, 2, 4, 5, 9 and 10, and including also an embracing band.

Figures 12 and 14 are fragmentary side views, showing modifications.

Figure 13 is an end view of a part shown by Figure 12.

The case consists in the first place of a rectangular body frame (Figure 1), creased at the corners, so that it will fold flat as seen in plan in Figure 2. This frame may be made of one piece A of board, as shown by Figure 1, for small packages, or of several pieces stitched together. For certain types of box the sides need not be the full depth, but composed of two or more strips A' stitched to the ends A² (Figure 3). Where strength is required the rectangular frame may be made of wood, the sides being hinged to the ends.

In the embodiment of the invention shown by Figures 4, 5, 6 and 11, I firmly attach to the ends of the body frame, end frames B, constituting abutments. These frames may have the form in section shown in Figures 4 and 5, so that a groove G is exposed all round the end of the rectangular frame A, for the insertion of the material composing the top and bottom members hereinafter described. As shown by Figure 6, the end frames, may be made of cardboard strips B', with stitched corners, and of such dimensions as to leave room between the strips and the body frame A, for the same purpose as the groove G. The end frames formed as shown in Figure 6 permit a sufficient collapse of the body frame A for practical purposes.

Figure 9 shows the construction of the parts forming the top and bottom members

C of the case, these members being identical, so that a description of one will suffice. Each member C is preferably made of a single piece, and rather longer than the body frame A. It is creased longitudinally along each side so as to form flanges C', to overlap the side of the body frame A, and if necessary, form entire external sides of the completed box. Preferably these flanges 10 are made half the depth of the body frame A, and each flange has a slot L extending from the edge to the crease, so that the top can be flexed, as shown in Figure 10, to shorten the distance between its ends and 15 permit said ends to be sprung into the grooves G in the end frames. When the bottom member has thus been inserted, the box stands up firmly for packing, and when the box is full, the top member is sprung into 20 position. The top and bottom members are then straightened by external pressure, to cause their ends to exert pressure in opposite directions on the abutments, by increasing the distance between said ends. The 25 said members are finally secured by suitable means to be presently described.

Owing to the fact that the straightened members C are longer than the body frame A, the ends of said members are thrust outwards and the body frame is put in tension. By securing the top and bottom members in this position, for example, by putting a band B² (Figure 11) tightly round the center of the box, a rigid case is formed, which 30 will resist great pressure on the ends and corners, without collapse when empty. Such pressure puts the said band in tension, and tends to burst it, so that it is only by the removal or destruction of the band that the case can be opened. The case cannot be pilfered, without destroying the means presently to be described, for retaining the band B² in position longitudinally, or damaging the case. In long cases, three or more bands 35 B² may be used. Where strength is not required, permanent cardboard bands, and for strong cases, hoop iron permanent bands may be used which will pass over the ends of the collapsed rectangular frame which is then expanded and the band placed near one end. The one end portion of each of the top and bottom members may be passed 40 under the band into the groove G, and the other end sprung into position in the opposite groove. The band, if a good fit, then requires much force to push it to its central position, where it is secured, and forms 45 a most rigid package.

In order to secure the bands in position, 50 eyelets E (Figures 11, 12 and 14), are permanently placed in the flanges C', near the central slots, and strings or wires W passed through the eyelets, so that when the band is in place, it lies just between two eyelets, and the string is tied, or the wire twisted 55

over the band and suitably sealed, for example, by a lead seal, so that the band cannot be displaced until the string or wire is cut. The band may then be removed and the case opened, repacked with other 70 goods, or dismembered into its several parts, and folded up and stored or returned in little space to the sender for reuse, every part, even the band being intact and undamaged. 75

Another method of closing the case is shown in Figures 12 and 13. Eyelets E are placed as before, and a permanent plate P of metal, bent so as to have a section as seen in Figure 13, is passed into the slot L so in the flange C' of the bottom member, so that the central web of the plate is in the slot. When the member C has been sprung into place, the plate P is moved up so as to embrace the edges of the slot in the flange 85 of the top member. Notches N (Figure 12) are cut in the edges of the plate P so as to correspond with the position of the eyelets, and the string or wire W engages in these notches and is tied or twisted, and 90 sealed, thus securing the plate in place and effectively preventing the removal of the top or bottom member. For light goods, the plate may be dispensed with, and the strings or wires W used to bind the top and 95 bottom members together, as shown in Figure 14. In opening the case, nothing except the string or wire is destroyed or damaged.

Figures 7 and 8 show the body frame provided with abutments, by means other than the end frame shown by Figures 4, 5, 6 and 11. These figures show the body frame here designated A³, provided with stout staples S, projecting outward. The flanges C' of the members C are provided with slots T forming tongues T' (Figure 9), adapted to enter said staples. The portions of the staples which encounter the ends of the slots T constitute abutments having the same function as those above described. 100

Figures 7 and 8 show the body frame A³ provided with abutments, by means other than the end frame shown by Figures 4, 5, 6 and 11. These figures show the body frame here designated A³, provided with stout staples S, projecting outward. The flanges C' of the members C are provided with slots T forming tongues T' (Figure 9), adapted to enter said staples. The portions of the staples which encounter the ends of the slots T constitute abutments having the same function as those above described. 105

Each end portion of the body frame A³ may have an extension A⁴ (Figure 7), provided with slots s, arranged to receive tongues on the end portions of the top and bottom members. The extensions A⁴ in this case constitute the abutments, and the slots s constitute equivalents of the grooves G. 110

Claims:

1. A box or packing case comprising a rectangular open body frame forming four upright box wall portions, abutments being provided at opposite end portions of the body frame; top and bottom members formed to close the top and bottom of the body frame, and having end portions formed to engage said abutments, said members being adapted to be flexed to decrease the distance between its end portions, and straightened to increase said distance, the arrangement being such that when said members are 120

125

130

- flexed, their end portions are engageable with said abutments, and when the members are straightened, their end portions are pressed in opposite directions against the 5 abutments, whereby the said body frame is put under tension, and said members are put under compression; and securing means 10 releasably confining said members in their straightened form.
- 10 2. A box or packing case substantially as specified by claim 1, said abutments being embodied in end frames fixed to opposite end portions of said body frame, and forming grooves adapted to receive the end portions 15 of said top and bottom members.
- 15 3. A box or packing case substantially as specified by claim 1, said securing means including a band surrounding the body frame and the said top and bottom members, and confining said members in their straightened form, and fastenings preventing 20 longitudinal displacement of said band.
- 20 4. A box or packing case substantially as specified by claim 1, said top and bottom members being provided with flanges overlapping opposite wall portions of the body frame, and having transverse slots permitting 25 flexure of said members.
- 25 5. A box or packing case substantially as specified by claim 1, said top and bottom members being provided with flanges overlapping opposite wall portions of the body frame, and having transverse slots 30 permitting flexure of said members, the said securing means including a band surrounding the body frame and the top and bottom members, and fastenings releasably connecting said band with the said flanges. 35
- 35 6. A box or packing case comprising a rectangular open body frame forming four upright wall portions, abutments composed of end frames fixed to opposite end portions of the body frame and forming therewith confining means, said body and end frames being flexible at their corners, and constituting a collapsible structure adapted to be flattened, top and bottom members formed to close the top and bottom of the body frame, and having end portions formed to engage said abutments, said members being adapted to be flexed to decrease the distance between its end portions, and straightened to increase said distance, the arrangement being such that when said members are flexed, their end portions are engageable 40 with said abutments, and when the members are straightened, their end portions are pressed in opposite directions against the abutments, whereby the said body frame is put under tension, and said members are put under compression; and securing means 45 releasably confining said members in their straightened form. 50
- 50 In testimony whereof I have affixed my signature.
